US0D1045054S

(12) **United States Design Patent** (10) **Patent No.:** **US D1,045,054 S**
(45) **Date of Patent:** **** Oct. 1, 2024**

(54) **CEILING FAN WITH LIGHT**

(71) Applicant: **Zhaoqing Yitai Intelligent Technology Co., Ltd.**, Zhaoqing (CN)

(72) Inventor: **Rongqing Du**, Nanchong (CN)

(73) Assignee: **Zhaoqing Yitai Intelligent Technology Co., Ltd.**, Zhaoqing (CN)

(**) Term: **15 Years**

(21) Appl. No.: **29/848,792**

(22) Filed: **Aug. 5, 2022**

(51) LOC (14) Cl. **23-04**

(52) U.S. Cl.

USPC **D23/377**

(58) **Field of Classification Search**

USPC D23/370, 377, 385, 411, 413; D26/59
CPC F04D 25/0673; F04D 25/088
